R. C. RUSSELL

CARD INDEX

Filed Oct. 2, 1923

UNITED STATES PATENT OFFICE.

ROBERT C. RUSSELL, OF PITTSBURGH, PENNSYLVANIA.

CARD INDEX.

Application filed October 2, 1923. Serial No. 666,101.

To all whom it may concern:

Be it known that I, ROBERT C. RUSSELL, a citizen of the United States, and resident of Pittsburgh, in the county of Allegheny and State of Pennsylvania, have invented 5 certain new and useful Improvements in Card Indexes; and I do hereby declare the following to be a full, clear, and exact description of the invention, such as will enable others skilled in the art to which it appertains, to make and use the same.

This invention relates to improvements in card indexes of the "visible" type and more particularly to means, such as a shield, to 15 protect the free edge portion of the cards against injury or soiling,—an object of my present invention being to provide simple and efficient means for attaching the shield to the card without riveting, cementing or 20 otherwise permanently securing the shield or protector to the card, and at the same time insure attachment of the shield to the card so that its accidental displacement will be prevented.

25 With this and other objects in view, the invention consists in certain novel features as hereinafter set forth and pointed out in the claims.

In the accompanying drawings;

30 Figure 1 is a front view of an index card showing the application of my improvements thereto;

Figure 2 is a rear view;

35 Figure 3 is a horizontal sectional view on the line 3—3 of Figure 1, and

Figure 4 is a vertical sectional view on the line 4—4 of Figure 1.

In the drawing, an index card is shown at 1, and at its respective ends, near its 40 lower edge, it is provided with notches or recesses 2, each having an inclined edge 3 and an upper horizontal edge 4.

A shield or protector 5 preferably of 45 transparent material, such as celluloid, is applied to the front face of the card near its lower free edge portion, and the lower edge of said shield is made with a small flange 6 which projects under the free edge of the card in a manner to protect said free 50 edge and also assist in preventing upward displacement of the shield.

At its respective ends, the shield is provided with integral, resilient tongues or pro-

jections 7 which may be triangular in form. These tongues are bent on bevel lines and are 55 disposed at the back of the card and at their beveled union with the body of the shield, engagement of the shield with the inclined edges 3 of the recesses 2 in the card, is effected, so that accidental displacement of the shield in any direction will be guarded against. By reason of the resilience 60 of the tongues 7, they will form clamps to engage the card and prevent attachment of the shield to the card from becoming loose. 65

Having fully described my invention what I claim as new and desire to secure by Letters-Patent, is:—

1. The combination with an index card and a protecting shield covering a lower 70 portion of a face of the card, said shield provided at its ends with members to engage the other face of the card, said shield also having a flange at its lower edge disposed under the lower edge of the card. 75

2. The combination of an index card and a protecting shield covering a lower portion of a face of the card, said shield provided at its ends with resilient members to engage the other face of the card, said shield 80 also having a flange at its lower edge disposed under the lower edge of the card.

3. The combination of an index card having notches in its ends near its lower edge, each of said notches having an inclined 85 edge, and a shield on the lower portion of a face of the card and provided at its ends with resilient tongues to engage the other face of the card, said shield engaging the inclined walls of said notches at the junction of said tongues with the body of the shield. 90

4. A shield for an index card, provided at its respective ends with resilient tongues bent on beveled lines and disposed approximately parallel with the body portion of the shield, said shield having a flange at its lower edge which projects at approximately right angles from said lower edge. 95

In testimony whereof, I have signed this 100 specification in the presence of two subscribing witnesses.

ROBERT C. RUSSELL.

Witnesses:

EDWARD E. DUFF,
JOHN T. CLARK.
